CLAIM

We claim the ornamental design for an absorbent article, as shown and described.

DESCRIPTION

FIG. 1 is a perspective view of an absorbent article according to a third embodiment of the present invention;
FIG. 2 is a top plan view of the absorbent article according to the embodiment of FIG. 1;
FIG. 3 is a side view of the absorbent article according to the embodiment of FIG. 1;
FIG. 4 is a bottom plan view of the absorbent article according to the embodiment of FIG. 1;
FIG. 5 is a first end view of the absorbent article according to the embodiment of FIG. 1; and,
FIG. 6 is a second end view of the absorbent article according to the embodiment of FIG. 1.
